UNITED STATES PATENT OFFICE.

HARRY H. FOX, OF DUQUESNE JUNCTION, PENNSYLVANIA.

TRACTION-INCREASING DEVICE FOR STREET-CARS.

No. 821,352.

Specification of Letters Patent.

Patented May 22, 1906.

Application filed December 5, 1905. Serial No. 290,445.

To all whom it may concern:

Be it known that I, HARRY H. FOX, a citizen of the United States of America, residing at Duquesne Junction, in the county of Allegheny and State of Pennsylvania, have invented certain new and useful Improvements in Traction-Increasing Devices for Street-Cars, of which the following is a specification, reference being had therein to the accompanying drawings.

This invention relates to certain new and useful improvements in traction-increasing devices for street-cars, and more particularly to an electrically-operated traction-increasing device.

The primary object of this invention is to employ the source of electrical energy employed for operating the car as a traction-increasing medium, and in accomplishing this result I entirely dispense with wheel-brakes, track friction-brakes, and brakes heretofore used for retarding and eventually stopping the car, as my improvement will serve to bring the car to a stop without the aid of braking devices. To this end I employ electromagnets, which are carried below the bottom of the car and have their cores arranged in close proximity to the rails over which the car travels. Upon energizing the electromagnets by passing an electric current through the same the cores of said magnets are strongly magnetized, and the attraction established between the magnetized cores and the rails over which the car travels serves to retard the movement of the car and eventually stop the same. I employ a conventional form of electromagnets which are suitably housed beneath the car and employ the ordinary controllers of a car for governing the operation of the electromagnets.

The detail construction of my invention will be hereinafter more fully described and claimed, and, referring to the drawings accompanying this application, like numerals of reference designate corresponding parts throughout the several views, in which—

Figure 1 is a fragmentary side elevation of a car equipped with my improvement. Fig. 2 is an end view of the same, and Fig. 3 is a diagrammatic view of the circuit employed in connection with the electromagnets.

In the accompanying drawings the reference-numeral 1 designates the body of the car, 2 2 the platforms thereof, which carry controller 3, and 4 the running-gear of the car.

My invention resides in placing two powerful electromagnets 5 5 at each end of the car, said electromagnets being of a conventional form having cores 6 6, which are controlled by an electric current passing through windings of insulated wire which surround said cores. The cores are preferably made of soft iron, which only remains magnetized while a current is flowing through the wire 65 windings of the magnets.

The electromagnets at each end of the car are identical in construction. Therefore I deem it only necessary to describe the construction of one set of magnets. The magnets are supported in a strap or yoke 7, connected to the body of the car, as at 8 8. The magnets are located above the rails 9 9, upon which the car travels, and the strap or yoke which supports said magnets may be suitably braced, as at 10 10.

In Fig. 3 of the drawings I have illustrated the wiring of said magnets, where it will be observed that the magnets are connected together by a wire 11, while a wire 12 leads 80 from one of said magnets to the source of electrical energy 14, and a wire 15 from the other of said magnets leads to a switch 16. Another wire 17 leads from the source of electrical energy 14 to the switch 16, where a lever or key 18 controls the magnetization of the electromagnets. 66.

When the lever or key 18, which is carried by the controller 3, or located adjacent thereto, is manipulated to energize the magnets 5 5, a current of electricity passes through said magnets which magnetizes the cores 6 6 and causes an attraction to be established between the rails of the track and said cores. The energizing of the electromagnets will 95 cause the rails to be strongly attracted by the magnets, and the attractive force thus produced will tend to draw the cars down so strongly as to retard their movement and eventually result in the stopping of the cars. 100

In order that my improved traction-increasing device will properly operate, it is necessary that the key or lever 18 be manipulated to establish circuit through the electromagnets, and thereby establish a mutual attraction between said magnets and the rails upon which the car travels.

It is obvious that various means, such as a rheostat, may be employed for governing the amount of electrical energy passing into the 110 electromagnets.

Such changes in the construction and op-

eration of my improvement as are permissible by the appended claims may be resorted to without departing from the spirit and scope of the invention.

5 What I claim, and desire to secure by Letters Patent, is—

1. In a traction-increasing device, the combination with a car, and the operating electric circuit thereof, of a plurality of pairs of electromagnets, immovably mounted on the bottom of said car, one pair being located at each end of the car, and beyond the wheel-base, one magnet of each pair being over one rail and the other magnet of the same pair being over the other rail, the said magnets being included in the said operating-circuit.
- 10
- 15

2. The combination with a car and the operating electric circuit thereof, of a yoke attached to the bottom of the car at each end thereof, and extending laterally beyond the 20 wheels, a pair of electromagnets mounted in each yoke with one magnet over one rail and the other magnet over the opposite rail, said magnets being in circuit with the operating-circuit of the car.

25 In testimony whereof I affix my signature in the presence of two witnesses.

HARRY H. FOX.
